[57] CLAIM

The ornamental design for a luggage case, as shown and described.

DESCRIPTION

FIG. 1 is a perspective view of a luggage case showing my new design, the essential feature of which resides in the configuration and appearance of the side panels thereof, it being understood that both sides and ends of the luggage case are identical in configuration and appearance to that shown; FIG. 2 is a bottom perspective view thereof.

Fig. 1.

Fig. 2.
